UNITED STATES PATENT OFFICE.

GOMER W. EDWARDS, OF JOHNSTOWN, PENNSYLVANIA.

CAN-OPENER.

1,265,760.

Specification of Letters Patent.

Patented May 14, 1918.

Application filed September 12, 1916. Serial No. 119,686.

To all whom it may concern:

Be it known that I, GOMER W. EDWARDS, a citizen of the United States, residing at Johnstown, in the county of Cambria and State of Pennsylvania, have invented certain new and useful Improvements in Can-Openers, of which the following is a specification.

The present invention relates generally to improvements in can openers.

The invention has more especial reference to a device for punching a vent opening and a liquid dispensing opening in the top of a can, such as one containing condensed milk, whereby the contents of the can may be more easily and conveniently dispensed.

More particularly, the present invention has reference to a device of the character mentioned formed from a single strip of material bent upon itself to provide a base and an arm, a punching element depending from the arm being adapted to provide a hole in the top of a can when the arm is depressed toward the base.

It has been the custom heretofore when opening cans of evaporated milk, syrup, etc., to employ a knife or other article that happens to be nearby for punching holes in the can but such articles are very unsatisfactory for this purpose.

Among the other aims and objects of this invention may be recited the provision of a device of the character mentioned with a view to compactness, the number of parts of which are few, the construction simple, the cost of production low, and the efficiency high.

Other improvements and novel details in the construction and arrangement of parts will be appreciated from the detail description below, which is to be read in connection with the accompanying drawings forming a part hereof, and wherein I disclose a preferred embodiment of the invention for the purpose of illustration.

The invention is clearly illustrated in the accompanying drawings in which:

Figure 1 is a side elevation of my invention in position on top of a can.

Fig. 2 is a perspective of the invention.

Similar characters of reference are employed in all of the above described views, to indicate corresponding parts.

Referring now more particularly to the

accompanying drawings I provide my novel can opener or device for punching holes in the tops of cans, said device being formed from a single strip of resilient metal bent upon itself to provide a base and an arm 2 the latter being yieldable with respect to the base. As is apparent in Fig. 1 of the drawings the base rests on the top of a can 3, a guide 4 being struck out from the base adjacent the outer end to consequently provide an opening 5, the said guide serving to properly position the base on the can.

Now, in order to punch a vent opening and a dispensing opening in the top of the can I have struck out a spur shaped punching element 6 from the arm 2 adjacent the outer end thereof, said punching element depending from the arm and being arranged so as to pass through the opening 5 when the arm 2 is depressed. Desirably the outer portions of both the base and the arm are enlarged so that the base will effectively support the device and so that the arm will be wide enough as to be readily engaged by the thumb of the user.

The mode of operation of the invention may be reviewed as follows:

Assuming that the device is in the position shown in Fig. 1, the guide 4 serves to properly position the same and by placing the thumb on the arm and depressing the arm, the punching element 6 will be forced through the opening and also through the top of the can. When pressure is removed from the arm, because of its resiliency it will resume its former position whereupon the device can be moved and adjusted in another position and operated in a similar manner to provide the other opening in the top of the can.

While I have illustrated and described a preferred embodiment of the invention, I am aware that many modifications may be made therein by any person skilled in the art without departing from the scope of the invention as expressed in the claim. Therefore, I do not wish to be limited to all the details shown, but

What I do claim is:

As a new article of manufacture, a can opener formed from a single piece of material bent into U-shape and having a cutter tongue formed by striking a triangular piece from one of the limbs adjacent the

2
end, which tongue is bent inward and projects toward the opposite limb, a bearing and spacing member formed by striking a tongue from the other limb, which tongue is bent downward and extends approximately at right angles to said latter limb, said cutter being operative within the hole produced by striking out the tongue, when the limbs

have their free ends moved toward each other.

In testimony whereof I affix my signature in presence of two witnesses.

GOMER W. EDWARDS.

Witnesses:

LAURENCE EDWARDS,
ALEX N. HABT.
